UNITED STATES PATENT OFFICE.

BRYCE W. McCLYMONT, OF DETROIT, MICHIGAN, ASSIGNOR TO PENBERTHY INJECTOR COMPANY, OF DETROIT, MICHIGAN, A CORPORATION OF MICHIGAN.

VACUUM-GENERATOR FOR STEAM-HEATING SYSTEMS.

1,388,871.

Specification of Letters Patent. Patented Aug. 30, 1921.

Application filed November 27, 1918. Serial No. 264,409.

To all whom it may concern:

Be it known that I, BRYCE W. McCLYMONT, a citizen of the United States, residing at Detroit, in the county of Wayne and 5 State of Michigan, have invented certain new and useful Improvements in Vacuum-Generators for Steam-Heating Systems, of which the following is a specification.

My present invention relates to a hydraulic apparatus operated by the flow of water from a supply under pressure, as the service pipe of a municipal water system, and is more particularly intended for producing and maintaining a low pressure in 10 the air pipe passages of heating systems in which steam conducted into the heating coils of radiators in the different compartments of a building is used as the heating agent. My new apparatus is in the nature of a 15 modification of and an improvement upon a hydraulic vacuum generator or pump described in McClymont Patent No. 1,265,928, issued on May 14th, 1918. The general object of my invention is to render such a device as that illustrated and described in said 20 patent automatic in a positive and reliable manner, and to so arrange and construct the parts through which the automatic action is attained as to produce a simple, efficient and 25 desirable device, well adapted for the purposes for which it is intended. With the foregoing and incidental objects and advantages in view, I have designed and invented the improved apparatus hereinafter 30 more fully described, the essential elements 35 of my invention being pointed out in the appended claims, it being understood, however, that my invention may be modified in the form and proportions of parts without 35 departing from the spirit of my invention or the scope of such claims.

In the drawings Figure 1 is a diagrammatic view of a heating system provided with a vacuum generating device embodying my invention, and Fig. 2 is a central longitudinal section of the device itself.

The same reference characters indicate the same parts wherever applied in the drawings.

50 In Fig. 1 of the drawings I have illustrated my invention as applied to a "double pipe" heating system, although, as later explained, it may be used equally well with a single pipe installation. As shown in said

figure, and in accordance with well known 55 practice, steam generated by the boiler 1 is conducted through the steam pipes 2 to the radiators 3 wherever located, and return pipes 4 are provided which conduct the water of condensation back to the lower part 60 of the boiler. Thermostatic air valves 5, constructed to permit the passage of cold vapor and to close quickly by the action of heat, whereby they close when acted upon by steam, are arranged to control communication between the radiators and the return pipes 4 of the system, the main return pipe being connected with the vacuum generator at some convenient point above the water level of the boiler by an air pipe 7 serving 70 as an air trap for the collection of water vapor and air.

The vacuum generating device to which my invention relates includes an ejector having valve-governed communication with the 75 water under pressure, as the service pipe 8, and a suction or vacuum chamber in communication with the air pipe 7 (in the present instance through a float valve and check valve controlled passage,) such vacuum 80 chamber being also in communication with the closed chamber of a spring-tensioned diaphragm which is operatively connected with the valve governing the passage of water through the ejector.

The admission valve 9 of the vacuum pump may conveniently be mounted in a valve body 10 having an apertured partition 11 formed with a valve seat, and also having a vertical cylindrical extension 12 in which 90 is arranged a stuffing box 13 for the valve stem 14. Below the stuffing box the extension 12 is formed with a cylindrical cushioning chamber 15 adapted to receive and slidingly engage the longitudinally grooved 95 upper portion of the valve 9, which is rotatably connected with the stem 14.

The valve body 10 makes screw-threaded engagement with the outer end of the jet member 16 of the ejector, such jet member 100 being also provided with threads engaging a threaded seat in the injector casing 17. Opposite the inner end of the jet the casing is followed out to form the vacuum chamber, and its forward tubular end extends upwardly in the form of an ogee curve. Mounted in the injector casing concentrically of jet 16 is a nozzle member 18, the

forward end of the jet projecting a short distance into the rear end of the nozzle. As shown, the forward or discharge end of the ejector passage, communicating with the sewer or other outlet, is governed by a check valve 19.

The diaphragm casing may conveniently be made in two parts, the lower section 20 being formed with a hollow externally threaded nipple 21 engaging a seat in the injector casing and providing communication with the vacuum chamber thereof. The flexible diaphragm 22 is secured between the lower section 20 and the upper section 23 of the diaphragm by a series of bolts 24, one of which, marked 24^a, extends through the casing sections and engages an internally threaded post on the front end of the ejector casing. The upper section 23 of the diaphragm casing is centrally apertured to accommodate a link 25 the lower end of which is secured to the diaphragm and the upper end of which has a one way or lost motion engagement with an operating lever 26.

This operating lever is flexibly connected at one end to the ejector casing through a link 27, and its other end is pivotally connected to the upper end of the valve stem 14, hereinbefore described. Interposed between the cap of the stuffing box 13 of the valve and an adjusting nut 28 mounted on the threaded upper end of the stem 14 is a compression spring 29, the tension of which stresses the diaphragm upwardly.

The vacuum chamber of the device is arranged to communicate with the air pipe system, in the present instance, though not necessarily, through a combined check and float valve device forming part of a heating system which constitutes the subject matter of my separate application No. 264,410 filed November 27, 1918, and is therefore not herein specifically claimed. It will therefore suffice to briefly explain that this device consists of a float chamber 30 within which is arranged a float 31 provided with a hollow stem which at its upper end carries a valve 32 adapted to shut off the passage of fluid into the vacuum chamber, this float valve having a projecting pin 33 which as such valve closes contacts a ball check valve 34 arranged in the passage opening into the vacuum chamber.

The manner in which my improved vacuum generating apparatus operates will readily be understood from the foregoing description of its mechanical construction and arrangement. When the heating system is in operation a shut-off valve 35 (which is closed when the system is idle) stands constantly open to permit the ejector to operate under certain conditions. Assuming the heating system to have been standing idle, the piping will be filled with cold air and water vapor and the stress of the spring 29

will cause the valve 9 to stand open. Upon opening the shut-off valve to admit water under pressure the action of the ejector will create a suction in the vacuum chamber which will draw the cold air from the radiators ahead of the steam which at the time is flowing into the radiators from the boiler and steam pipes. As soon as the steam reaches the thermostatic valves 5 they automatically close, and the action of the ejector thereupon still further reduces the air pressure in the vacuum chamber until the preponderance of atmospheric pressure upon the outside of the diaphragm, acting through the link 25 and lever 26, becomes such as to overcome the resistance of the spring 29, shifting the valve 9 gradually down to its seat and stopping the exhausting action of the ejector. The check valve 19 immediately closes, thus maintaining the vacuum in the vacuum chamber and air pipes, and through the action of the diaphragm 22 the valve 9 is held closed. This is the normal condition of the parts while the heating system is in use, shown in full lines in Fig. 2, the position of the diaphragm and connected lever 26 when the heating system is idle being indicated in dotted lines. Should the vacuum in the air system diminish,—i. e. the pressure increase,—through leakage or the cooling of any thermostatic valve and the passage of air or vapor therethrough, the reduced effect of atmospheric pressure on the outer face of the diaphragm will permit the spring 29 to open the valve 9 and increase the vacuum until the valve is again closed by the reduction of pressure.

In case the vacuum should be so great as to lift water of condensation to the level of the ejector passage the float valve 32 prevents it from being carried into the sewer instead of being returned to the boiler. The ball check valve 34 provides a further safeguard, additional to the check valve 19, against leakage of air back into the air pipe system. It is obvious, however, that if desired the air-pipes may communicate directly with the vacuum chamber of the device and the float valve and ball check valve be dispensed with.

In installations employing a single pipe system, such as illustrated in McClymont Patent No. 1,265,928, before mentioned, the steam pipes are connected to the lowermost part of the radiators so that any water of condensation which may form will flow back to the boiler by gravity through the steam pipes. In such systems small return air pipes for the return or venting of air only connected to the upper part of the radiator and conducted to a convenient point adjacent the boiler are provided, and this connected system of air pipes communicates through a drain passage with the lower part of the boiler for returning to it whatever

water of condensation may pass into such air pipes. In an installation of this description the connection to the combined float and check valve of the vacuum generator is made 5 in the same manner as the connection with the air pipe of the double pipe system hereinbefore described.

I claim:

1. In a device of the character described, 10 an ejector casing having inlet and outlet openings and a vacuum chamber and ejector members arranged to produce a vacuum in said chamber, a diaphragm casing mounted on said ejector casing and a diaphragm ar- 15 ranged therein, one side of said diaphragm being subject to the pressure in said vacuum chamber and the other side exposed to atmospheric pressure, a valve casing and an admission valve therein arranged adjacent 20 the inlet of said ejector casing, said valve having a valve stem, a lever pivotally connected with said valve stem and also flexibly connected with said ejector casing, a link connecting said diaphragm and said lever, 25 a spring tending to open said valve, and a check valve at the outlet opening of said ejector casing.

2. In a device of the character described, 30 an ejector casing having inlet and outlet openings and a vacuum chamber and ejector members arranged to produce a vacuum in said chamber, a diaphragm casing mounted on said ejector casing and a diaphragm ar- 35 ranged therein, one side of said diaphragm being subject to the pressure in said vacuum chamber and the other side exposed to atmospheric pressure, a valve casing and an admission valve therein arranged adjacent 40 the inlet of said ejector casing, said valve having a valve stem, a lever pivotally connected at one end with said valve stem and extending diametrically over said diaphragm casing and flexibly connected at its other end with said ejector casing, a link connect- 45 ing said diaphragm and said lever, a spring

tending to open said valve, and a check valve at the outlet opening of said ejector casing.

3. In a device of the character described, an ejector casing having inlet and outlet openings and a vacuum chamber and ejector members 50 arranged to produce a vacuum in said chamber, a diaphragm casing mounted on said ejector casing and a diaphragm arranged therein, one side of said diaphragm being 55 subject to the pressure in said vacuum chamber and the other side exposed to atmospheric pressure, a valve casing and an admission valve therein arranged adjacent the inlet of 60 said ejector casing, said valve having a valve stem, a lever pivotally connected with said valve stem and also flexibly connected with said ejector casing, a link connecting said diaphragm and said lever, a coiled compression spring surrounding said valve stem and 65 yieldingly tending to open said valve, and a check valve at the outlet opening of said ejector casing.

4. In a device of the character described, 70 an ejector casing having inlet and outlet openings and a vacuum chamber and ejector members arranged to produce a vacuum in said chamber, a diaphragm casing mounted on said ejector casing and a diaphragm arranged therein, one side of said diaphragm being 75 subject to the pressure in said vacuum chamber and the other side exposed to atmospheric pressure, a valve casing and an admission valve therein arranged adjacent the inlet of said ejector casing, said valve having a threaded valve stem, a lever pivot- 80 ally connected with said valve stem and also flexibly connected with said ejector casing, a link connecting said diaphragm and said lever, an adjusting nut mounted on said valve stem, a coiled compression spring sur- 85 rounding said valve stem and yieldingly tending to open said valve, and a check valve at the outlet opening of said ejector casing.

BOYCE W. McCLYMONT.
